COMBINED LID OPENER AND HINGE FOR
GARBAGE RECEPTACLES

Earl W. Edwards, South Pasadena, Calif.

Application July 6, 1948, Serial No. 147,389

Term of patent 14 years

(CL. D10—9)

To all whom it may concern:

Be it known that I, Earl W. Edwards, a citizen of the United States, residing at South Pasadena, in the county of Los Angeles and State of California, have invented a new, original, and ornamental Design for a Combined Lid Opener and Hinge for Garbage Receptacles, of which the following is a specification, reference being had to the accompanying drawing, forming part thereof.

The figure is a perspective view of a combined lid opener and hinge for garbage receptacles, showing my new design.

I claim:

The ornamental design for a combined lid opener and hinge for garbage receptacles, as shown.

EARL W. EDWARDS.
